COMPACT SHAVING KIT

John Sottile, Mariners Harbor, N. Y.

Application October 15, 1953, Serial No. 335,191

1 Claim. (Cl. 220—20)

2

ing element 28 adapted to cooperate with a male snap fastening element 29 provided on the bottom wall 21 to secure the cover 25 in a closed position. A safety razor 30, a shaving brush 31 and a box of safety razor blades 32 are housed within the compartment 24 (Fig. 3).

As shown in Fig. 1, with the covers 14 and 25 snapped closed, the compact may be carried around by the strap 23 or carried in a pocket. When shaving, the cover 14 will be opened to provide the mirror 16 and the shaving soap 13 after the shaving brush 31 and razor 30 have been removed.

While various changes may be made in the detailed construction, it shall be understood that such changes shall be within the spirit and scope of the present invention as defined by the appended claim.

Having thus set forth and disclosed the nature of my invention, what is claimed is:

A compact shaving kit comprising a substantially flat rectangular casing, a first compartment at a first longitudinal end of said casing opening to the top of said casing, a second compartment at a second longitudinal end of said casing opening to the bottom of said casing, said first and second compartments lying between common parallel horizontal planes and being separated from each other by a transversely extending vertical wall disposed midway between said longitudinal ends of said casing, a first horizontal wall extending longitudinally from the lower edge of said vertical wall and forming a floor for said first compartment, a second longitudinal horizontal wall extending from the upper edge of said vertical wall in a direction opposite to said first horizontal wall and forming a floor for said second compartment, said vertical wall being of a height corresponding to the depth of each said compartment, a carrying handle disposed at said first longitudinal end of said casing, a first cover having vent openings hingedly connected to the top of said second longitudinal end adapted to overlie said first compartment, a second cover hingedly connected at the bottom of said second longitudinal end of said casing adapted to overlie said second compartment, said first cover extending between said second end and said first end of said casing and said second cover extending between said second end and said vertical wall of said casing, and releasable means for securing each of said covers in closed position.
